(57) **CLAIM**

I claim the ornamental design for a modular sport center, as shown and described.

DESCRIPTION

FIG. 1 A top plan view of the claimed design.

FIG. 2 A top front side perspective view of the claimed design.

FIG. 3 A top back side perspective view of the claimed design.

FIG. 4 A top front side perspective view of the claimed design; and,

FIG. 5 A top back side perspective view of the claimed design.
